UNITED STATES PATENT OFFICE.

LEWIS S. HOWARD, OF CHICAGO, ILLINOIS.

SIGNAL DEVICE.

1,259,516.

Specification of Letters Patent. Patented Mar. 19, 1918.

Application filed March 24, 1917. Serial No. 157,282.

To all whom it may concern:

Be it known that I, LEWIS S. HOWARD, a citizen of the United States, residing at Chicago, in the county of Cook and State 5 of Illinois, have invented new and useful Improvements in Signal Devices, of which the following is a specification.

This invention relates to signal devices and to one which is especially adapted for 10 use on automobiles to enable the driver to indicate movements which he purposes to give to the vehicle. It comprises essentially a simultaneously actuated signal carrier and shutter which coöperate to disclose the desired signal.

One preferred embodiment of my invention is shown in the accompanying drawings of which—

Figure 1 is a front elevation of the device 20 with an automobile number plate attached thereto;

Fig. 2 is a view of a horizontal section taken on the line 2—2 of Fig. 1;

Fig. 3 is a view of a vertical longitudinal 25 section;

Fig. 4 shows a cross section taken on the line 4—4 of Fig. 2;

Fig. 5 is a cross section taken on the line 5—5 of Fig. 2;

Fig. 6 is a diagram of the circuit connections to the several electromagnets; and

Fig. 7 is a perspective view of the drum showing the signals in their preferred position.

The device comprises a supporting plate 1 provided with suitable bolt holes so that it can be attached to the automobile and having hinged thereto a casing 2. This casing is provided with a light opening or window 3 through which the signals may be viewed and the customary red colored window 4; the casing is held in place against the supporting plate by a suitable fastening or locking device 5. The lower part of the plate 1 is provided with slots 6 for the reception of bolts carrying the number plate 7. The lower part of the casing has a narrow window 8 so that light from the lamp 9 may illuminate the number plate at night.

On a shaft 10 pivoted in the casing there is mounted a signal-carrying drum 11 the cylindrical portion of which is made of glass, celluloid, or other suitable transparent material. The cylindrical portion at one end is cut away at 12 to permit of the insertion of the lamp 9, the cut away por-

tion being of sufficient dimensions to permit said drum to turn part of a revolution in either direction. The drum is held in its normal resting position by a weight 13 which is connected to said shaft by gears 14 and 15, the latter being keyed to the shaft. One end 16 of the drum has an arm 17 which carries an arcuate solenoid plunger 18, the ends 19 and 20 of which are in operative relation with the solenoids 21 and 22, respectively. The plunger 18 carries projections 23 suitably spaced thereon so as to limit the movement of the plunger when it is attracted by a solenoid.

A shutter 24 normally extending across the light opening 3 is carried by sectors 25 and 26 which are mounted on the shaft 10. The sector 26 has an extension carrying a balancing weight 27. The inner side 75 of the sector 25 has an arm 28 which carries an armature in the form of a solenoid plunger 29 which is in operative relation with an electro-magnet such as the solenoid 30. On the free end of the plunger 29 there is mounted a weight 31 of sufficient proportions to balance the arm 28. The plunger 29 and solenoid 30 are so disposed with respect to the shutter 24 that when the solenoid is deenergized the weight of 80 the plunger 29 will be sufficient to hold the shutter in its normal non-signaling condition.

The signals "right," "stop" and "left" are affixed to the drum 11 in the order 90 named. When the device is in its non-signaling position the word "stop" faces the opening 3 but is hidden from view by the shutter 24.

The circuits are arranged as shown diagrammatically in Fig. 6, the battery 32 and the electromagnets 21, 22, and 30, being shown connected to ground. Closing of switch 35, which is preferably operated by a movement of the brake pedal, makes the 100 circuit through the shutter solenoid 30. Closing the switch 33 permits current to pass from wire 36 to wires 37 and 38 leading to the left and shutter magnets, respectively, while closing the switch 34 permits 105 current from the wire 39 to pass through wires 40 and 41 to the right and shutter magnets, respectively.

The device operates as follows:

When the stop signal is to be shown a 110 movement of the brake pedal or other suitable movement to close the switch 35 will

cause the solenoid 30 to be energized and attract the plunger 29; the shutter 24 is thereby turned to expose the signal "stop". When it is desired to signal the turning of the machine to the right the switch 34 is closed thereby causing the solenoids 22 and 30 to be energized and attract their respective plungers 20 and 29; as a result of this movement the drum 11 will be turned so that the word "right" is before the opening simultaneously with the turning of the shutter. When the left signal is to be given, the closing of the switch 33 will cause the solenoid 21 to turn the drum 11 so that the signal "left" is in front of the opening 3, while the solenoid 30 turns the shutter away from the opening.

Although I have described above one specific embodiment of my invention I wish it to be understood that various changes in details may be made within the scope of the appended claims.

I claim:

1. A signal device comprising a casing having a light opening for viewing a signal, a signal carrier opposite said opening and pivoted in the casing and carrying a plurality of signals, a shutter normally extending across said opening and pivoted in the casing, means for turning said shutter alone to disclose a signal, and means for turning both said shutter and said signal carrier to disclose another signal.

2. A signal device comprising a casing having a light opening for viewing a signal, a signal carrier opposite said opening and pivoted in the casing and carrying a plurality of signals, a shutter normally extending across said opening and pivoted in the casing, means for turning said shutter alone to disclose a signal, and means for turning said signal carrier coöperatively with the turning of said shutter to disclose any one of a plurality of other signals.

3. A signal device comprising a casing having a light opening for viewing a signal, a source of light in said casing, a drum opposite said opening and pivoted in the casing and carrying a plurality of signals, a shutter normally extending across said opening and pivoted in the casing and carrying an armature in operative relation with an elec-

tromagnet, an arcuate solenoid substantially concentric with said drum, an arcuate solenoid plunger in operative relation with said solenoid and fixed to said drum, means for energizing said electromagnet to turn said shutter alone to disclose a signal, and means for energizing said electromagnet and said solenoid at the same time to simultaneously turn said shutter and said drum to disclose another signal.

4. A signal device comprising a casing having a light opening for viewing a signal, a drum opposite said opening and pivoted in the casing and carrying a plurality of signals, a shutter normally extending across said opening and pivoted in the casing and carrying an armature in operative relation with an electromagnet, arcuate solenoids substantially concentric with said drum, arcuate solenoid plungers respectively in operative relation with said solenoids and fixed to said drum, means for energizing said electromagnet to turn said shutter only, means for energizing said electromagnet and for energizing selectively any one of said solenoids to simultaneously turn said shutter and said drum, and means for bringing said device back to its non-signaling condition when said magnets are deënergized.

5. A signal device comprising a casing having a light opening for viewing a signal, a drum opposite said opening and pivoted in the casing and carrying a plurality of signals, a shutter normally extending across said opening and pivoted in the casing and carrying an armature in operative relation with an electromagnet, two arcuate solenoids substantially concentric with said drum, a drum-attached arcuate solenoid plunger one end of which is in operative relation with one of said solenoids and the other end of which is in operative relation with the other of said solenoids, means for energizing said electromagnet to turn said shutter only and disclose a signal, and means for selectively energizing either one of said solenoids coöperatively with the energizing of said electromagnet to turn both said shutter and said drum and thereby disclose either one of two other signals.

In testimony whereof I affix my signature.
LEWIS S. HOWARD.
